[57] CLAIM

The ornamental design for a packaging container for dental materials, as shown.

DESCRIPTION

FIG. 1 is a top perspective view of a packaging container for dental materials showing my new design;

FIG. 2 is a front elevational view;

FIG. 3 is a top plan view;

FIG. 4 is an elevational view looking from the right of FIG. 2;

FIG. 5 is a rear elevational view;

FIG. 6 is a bottom plan view; and

FIG. 7 is another top perspective with dental materials being shown in broken lines to illustrate environmental use only.
